US0D1105613S

(12) **United States Design Patent** (10) **Patent No.:** **US D1,105,613 S**
(45) **Date of Patent:** **** Dec. 9, 2025**

(54) **NAIL CORRECTOR**

(71) Applicant: **Junnan Wu**, Lengshuijiang (CN)

(72) Inventor: **Junnan Wu**, Lengshuijiang (CN)

(**) Term: **15 Years**

(21) Appl. No.: **29/972,081**

(22) Filed: **Nov. 7, 2024**

(51) **LOC (15) Cl.** **24-99**

(52) **U.S. Cl.**

USPC **D24/192; D28/56**

(58) **Field of Classification Search**

(57) **CLAIM**

The ornamental design for a nail corrector, as shown and described.

DESCRIPTION

FIG. 1 is a perspective view of a nail corrector, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is a perspective view of a nail corrector on the toenail, shown in a used condition.

The broken lines showing a toe illustrate environment and form no part of the claimed design.

1 Claim, 9 Drawing Sheets
